UNITED STATES PATENT OFFICE.

WILBUR L. ORME, OF CAMBRIDGE, OHIO.

DESIGN FOR A SHAVING-COMPACT RECEPTACLE.

Application filed February 15, 1927. Serial No. 20,774. Term of patent 7 years.

To all whom it may concern:

Be it known that I, WILBUR L. ORME, a citizen of the United States, residing at Cambridge, in the county of Guernsey and State of Ohio, have invented a new, original, and ornamental Design for a Shaving-Compact Receptacle, of which the following is a specification, reference being had to the accompanying drawing, forming part thereof.

Fig. 1 is a side elevation showing my new shaving compact receptacle;

Fig. 2 is a top plan view thereof; and

Fig. 3 is a top plan view of the base, with the cover removed.

I claim:

The ornamental design for a shaving compact receptacle, as shown.

WILBUR L. ORME.
